UNITED STATES PATENT OFFICE.

MELVILLE CLARK, OF CHICAGO, ILLINOIS.

REED-ORGAN.

SPECIFICATION forming part of Letters Patent No. 310,933, dated January 20, 1885.

Application filed November 8, 1883. (No m.-del.)

To all whom it may concern:

Be it known that I, MELVILLE CLARK, a citizen of the United States of America, residing at Chicago, in the county of Cook and State of Illinois, have invented certain new and useful Improvements in Reed-Organs, of which the following is a specification, reference being had therein to the accompanying drawings.

10 My invention relates to that class of reed-organs in which, in addition to the ordinary mute of the reed-cells, an additional or auxiliary mute situated over the vibrating ends of the reeds is employed. Heretofore in the class referred to there have been three different constructions employed, as follows: first, where the auxiliary mute has opened into the organ, whereby the harsher tones are obtained; second, where the auxiliary mute has 20 been situated within a chamber provided with an inwardly-opening valve, and through which the valve-stems are passed, by means of which the harsher notes are obtained, and also, to a certain extent, the softer notes; and, third, 25 where the auxiliary mute has been situated within a chamber to which air is admitted only through the openings which are covered by said mute and through the pores of the wood forming said chamber, and by this last-named construction the softest notes have been obtained.

The object of this invention is to so arrange the parts that in the one instrument all the 30 harshest and softest notes may be obtained, and, further, to so arrange the openings covered by the auxiliary mutes that they may be applied to the entire instrument and facilitate the tuning of the same.

To the accomplishment of the above, the invention consists, first, in employing an additional swell, under which the additional mute is to be situated, and whereby all the advantages of a closed chamber and having the mute open into the interior of the instrument are obtained, and, secondly, in the particular arrangement of the openings covered by said additional mutes, said novel arrangement consisting in having all of such openings from "center C" through the treble of uniform size, 50 while those from the center C through the bass are graduated.

Reference will be made to the accompanying drawings, in which Figure 1 is a sectional view of an action; Fig. 2, a plan of the same with parts removed, and Fig 3 a view in detail showing arrangement of openings over the vibrating ends of the reeds.

Like letters refer to like parts in each view.

A denotes the reed-board, which is slotted to provide an air-passage, *a*, for each pair of reeds, 60 and through which communication is made with the wind-chest B below such reed-board, said openings being closed by cushioned valves C, oscillating on studs *b*, guided on steady-pins *c*, and pressed to their seats by springs *d*. 65

Upon the reed-board A are glued two longitudinally-tapering boards, D, one of which is shown in plan in Fig. 3. These boards are gouged out from their under sides through their exterior beveled edges, to form cells for 70 reeds *e* proportional to the increasing sizes of such reeds, which are shifted into bottom side grooves of such cells to lie close upon the reed-board A and over air-passages *a*. The end openings of these cells are closed by mutes E, 75 which are situated under swells F, both of which parts are suitably hinged, and adapted to be operated by the ordinary stops. Boards D, when in position, contact at their inner edges, and are provided with openings *f*, 80 through which valve stems *g* pass, as will be described.

Situated upon boards D is a strip, G, through which openings for the valve-stems are made. This strip extends the entire length of the instrument, and to each outer edge thereof is hinged a swell, H, as shown in Fig. 1. The outer or free end of each swell H rests upon a strip, I, which strips are secured upon the boards D, and which in height are a little less 90 than the strip G. Situated within the spaces or chambers formed by these strips and swells are the auxiliary mutes J, which cover a series of openings, K, formed in each of the boards D, and situated over the vibrating ends 95 of the reeds. These auxiliary swells and mutes are operated by any suitable stops.

The openings K, described as formed in boards D, are arranged as shown in Fig. 3. As shown in that figure, these openings from "middle C" throughout the treble end of the organ are of a uniform size, while those from

middle C throughout the bass are graduated, the largest of said openings being preferably one and one half inch, while the smallest is one-eighth of an inch, and, while the sizes 5 may be varied, the proportion should remain the same. This arrangement I have found necessary in order to tune the entire instrument, it being impossible where all the openings are of a uniform size or where they are 10 graduated throughout the instrument. I have also found that while the openings beneath the reeds may be graduated throughout the instrument the same arrangement will not answer for those over the reeds.

15 The arrangement of the reeds and the openings through which air is admitted thereto is such that air admitted to the reed-cell through the opening adapted to be closed by the ordinary mute is drawn down by the suction-bellow, while that admitted through the openings over the vibrating ends of the reeds is 20 forced into direct contact therewith, which difference in the direction of the air-currents renders necessary the different arrangement of 25 the two series of openings, as herein described and claimed.

By the employment of the auxiliary swells I am enabled to obtain all the softness of tone

consequent upon the use of a closed chamber, and at the same time all the advantages derived from having the auxiliary mutes exposed.

In the drawings, L is the key-board, and M one of the keys. I cover the openings formed at the end of the action for the auxiliary mutes with suitable leather or felt caps, N, such as are described in a former application made by me.

What I claim is—

1. The combination, with the ordinary mute and swell of a reed-organ, of an auxiliary swell 40 and an auxiliary mute situated under said swell, as and for the purpose set forth.

2. In a reed-organ, the board D, provided with a series of openings situated over the vibrating ends of the reeds and covered by auxiliary mutes, said openings being of uniform size from middle C throughout the treble, and graduated from middle C throughout the bass, as and for the purpose set forth.

In testimony whereof I affix my signature in 50 presence of two witnesses.

MELVILLE CLARK.
